TENSION CONTROLLING MEANS

Henry A. Wise Wood, New York, N. Y., assignor to
 Wood Newspaper Machinery Corporation, New
 York, N. Y., a corporation of Virginia

Application December 8, 1931, Serial No. 579,760
 Renewed March 12, 1934

4 Claims. (Cl. 242—75)

This invention relates to the means employed for controlling the speed of the web drawn off a supply roll and supplied to a machine, as for example, a printing press, and used to prevent 5 the web from racing.

The principal objects of this invention are to provide a tension device, in the form of one or more belts, with means for locking it so as to act as a stationary strap when normal tension is desired and which may be released so that it will run along with the paper and move with the same speed without providing any tension while the press is accelerated.

Other objects and advantages of the invention 15 will appear hereinafter.

Reference is to be had to the accompanying drawings, in which

Fig. 1 is an end view of a web roll supporting device with tension belts and a preferred embodiment of this invention applied thereto;

Fig. 2 is a side view of the same as indicated by the arrow 2 in Fig. 1, and

Fig. 3 is a view similar to Fig. 1 of the locking means in unlocked position to allow the web to move as fast as it is drawn into the press without applying tension.

This invention is particularly adapted for modern newspaper presses but capable of other uses. Such presses are supplied with paper from a paper roll as 10 and 11 and the tension can be secured in many ways. For the purpose of illustrating this invention it is shown as provided with tension belts 12 running against the surface of the supply roll 10 and, of course, when 30 the new roll 11 comes around that will come into position to receive tension from the same belts. In ordinary practice these presses are run at constant speed and it is necessary to provide only enough tension to keep the paper taut enough to 35 prevent its running ahead in the folder. No excessive strain is put on the paper when running at constant speed. However, when the press is started up it draws its paper from the full roll and there is an added strain on the paper owing 40 to the fact that this roll has to be brought up to speed by the pull of the web upon it.

When using a stationary strap, the normal tension is always present. With the running strap, which is run at a slightly less speed than 45 that of the paper to maintain normal tension, there is no assistance to the roll when the press is being accelerated.

In the particular form shown these straps or belts are made endless and capable of running 50 continuously. They are supported by a series

of idlers 13. I have shown the belts or straps 12, each as having a downwardly extending loop from two of these idlers and provided with a pulley 14 hanging in the loop. This loop has a yoke 15 carrying weights 16 to hold the belt tight and provide normal tension. Of course, in the case of a plurality of belts they will all be arranged in the same way preferably.

From what has been said it will be seen that the belts will run with the web if no restriction is provided and accomplish in that case no function. For the purpose of holding the belts stationary, each one of them is brought under and around a pulley 17 running freely, of course. This pulley is mounted in bearings on a stationary bracket 18 on which at one side is pivoted a brake shoe 19. This brake shoe is shown as swinging back by gravity into the position shown in Fig. 3 whenever released. In this position the belt does not supply any tension.

When tension is desired, a handle 20 on a locking eccentric 21 is turned, as shown in Fig. 1, to bring the eccentric or cam 21 upwardly and move the brake shoe 19 up into contact with the belt or strap. It will be seen that the eccentric is so shaped that when the handle is brought around to the position shown in Fig. 1 the brake shoe 19 will be held against the belt by the weight of the handle and the belt will be stopped, or the pressure may be only enough to retard the belt 25 but to let it run slowly and supply a small amount of tension. Thus it will apply the proper tension of a stationary strap to the web. This is the 30 normal running condition.

Now in starting the press or in starting a new 35 roll, the handle 20 is pulled or kicked over into the position shown in Fig. 3 against a stop 22 and the web then will be free to move as rapidly as the press will pull it in. This position is maintained only while the roll is being accelerated up 40 to full speed and then the operator moves the operating handle 20 back to the position shown in Fig. 1 and the belts act thereafter as stationary straps as stated above. One of these locks may be used for each strap and each one operated independently, if desired.

I have shown the manual operation of this release but, of course, I am not limited to the same as the operation of the press above described would otherwise be the same if the operation of 50 the lock were automatic. The invention is capable of use with other kinds of tension devices than straps and belts. I have shown the invention used in cooperation with mechanism 25 constituting a part of a splicing mechanism but the in- 55

vention is as easily applicable to paper carrying devices carrying no automatic splicing device.

It will be apparent therefore that mechanism is presented which permits the proper feeding of paper to a press with a minimum amount of strain, accomplished by releasing the tension on the paper roll during acceleration of the press.

Although I have illustrated and described only one form of the invention I am aware of the fact that modifications can be made therein by any person skilled in the art without departing from the scope of the invention as expressed in the claims. Therefore I do not wish to be limited in this respect, otherwise than as set forth in the claims, but what I claim is:—

- 15 1. In a device for controlling the operation of a tension belt, the combination of a pulley around which the belt passes, a brake shoe adapted to engage the belt passing around the pulley, and means for holding the brake shoe against the belt on the pulley.
- 20 2. In a device for controlling the operation of an endless tension belt, the combination of a pulley around which the belt passes, a brake shoe

adapted to engage the belt passing around the pulley and means for holding the brake shoe against the belt on the pulley, said means being easily releasable to allow the brake shoe to drop away from the pulley and belt to release the belt.

5 3. In a tension device for the purpose described, the combination of an endless belt having a downwardly extending loop, a pulley freely mounted in fixed bearings and located in said loop, a brake shoe pivoted at one side of the pulley and adapted to engage the belt, whereby when released it will drop down from its pulley by gravity and an eccentric device in position to engage the bottom of the brake shoe and move it into contact with the belt to stop or retard the 10 belt, for the purpose described.

10 4. In a tension device for the purpose described, the combination of a tension belt, a surface over which the belt is adapted to run, a brake shoe adapted to engage the belt to press it against said 15 surface to retard or stop the belt, and means by which the brake shoe is easily moved away from the belt to release it.
